ELECTRODE HOLDER

Fritz Lehrer, Berlin-Charlottenburg, and Johannes Wotschke, Berlin-Dahlem, Germany; vested in the Alien Property Custodian

Application October 4, 1940, Serial No. 359,812
In Germany October 9, 1939

2 Claims. (CL 13—14)

The invention relates to electrode holders consisting of two spaced superposed clamping jaw arrangements and with the aid of such a pair of clamps the electrode held therein is automatically finely adjustable when being fed, without loss of gripping security in all operating and regulating positions. According to this invention the superposed clamping arrangements are connected with each other, are positively locked and move in opposite directions preferably in such a manner that all force transmitting components are engaged only with respect to pull or pressure. The clamps may be provided with any number of jaws and also may be designed for current transmission, the part holding the electrode being of a design known for such purpose.

The positively locked connection of the two clamps moving in opposite directions has the effect that the grip of the lower clamp holding the electrode in operating position is necessarily weakened in the case of a contemplated re-adjustment of the electrode but only to such a slight extent that the electrode moves relatively to such clamp and, in fact, to the entire holder owing to the fact that the starting of the re-adjusting movement for loosening one of the clamps results in a corresponding pressing-on effect of the other clamp. In consequence thereof the feeding movement may be interrupted at any place and therefore may be as slight as desired. At the end of the adjusting movement the pressing-on force, stopping the electrode, will by itself increase again to the original value. The invention in view of this effect may be designated as a sliding holder with automatic regulation and fine adjustment.

The drawings show the invention in several modes of construction in lateral view and the individual components in sectional view. Corresponding components in the various figures are provided with the same symbols.

Figure 1 shows a simple mechanical design of the new sliding holder.

Figure 2 shows a sliding holder with mechanical force-operated arrangement and common actuation of all re-adjusting members of the upper clamp.

Figure 3 shows a hydraulically actuated sliding holder.

Figures 4, 5 and 6 represent in longitudinal section and greatly enlarged the bearing of a drawbar in various positions.

Figure 7 shows in centre longitudinal section with individual components a fourth mode of construction according to the invention.

In Figure 1 the electrode 1, which simultaneously may be designed for current transmission, is held by jaws, the spring power being adjustable as to its value by means of a rod 5 arrangement for subjecting the jaws to pressure. For this purpose the tension of spring 2 is transmitted in the casing 7 by way of the crosshead 3 and by means of the toggle 4 to the slidable piston 5, which, in turn, exerts pressure on the jaw 6 thereby maintaining the electrode 1 in position. These elements are accommodated in recesses of a ring 8 surrounding the electrode and being so dimensioned as to be equal to the stress of all occurring forces.

Over this main clamp the electrode 1 is grasped by a pair of tongs. The mouth 14 of the tongs is so designed that with a downward movement of the tongs automatic checking will take place and the clamping effect on the electrode will increase in keeping with the increase of the force acting in downward direction on the legs 11 of the tongs. With an upward movement of the tongs the mouth 14 of the tongs tends to open in response to the effect of the moment caused by the frictional force and thus opposes the upward movement by a but very small force scarcely impeding such movement. The bar 9, on which the spring 2 is exerting its compressive force, passes through this spring and its upper part is designed as a screw extending through the legs 11 of the tongs. Thus a travelling nut 10 which, on the one hand, is screwed onto the spindle 9 and, on the other hand, is rotatably connected to the leg 11 of the tongs, with a movement of the spindle 9 takes compulsorily with it the leg 11 of the tongs. On turning the nuts simultaneously, for example, over a chain drive 13, the nuts will at first move downward only as far as is permitted by the backlash. Downward sliding off of the tongs is prevented by their automatic stopping. Thus, continued turning of the screws will result in a pulling force opposed to and weakening the spring power. The pressure at the jaw 6 is thus reduced, but the downwardly directed weight of the electrode 1, having so far been balanced by the frictional force caused by the spring power at the jaws, is augmented by the reactive force transmitted by the tongs 14 to the electrode 1, causing sliding of the electrode. The electrode continues to slide as long as the equilibrium is interfered with by the turning of the screws. On ceasing turning the screws 10, the force weakening the springs 2 caused by the turning of the screws will dis-

appear and the spring will again press with its full tension on the jaws 6 and hold the electrode 1.

The electrode may be relieved by one uninterrupted move or at intervals until the tongs come to rest on the ring. By turning the nuts in opposite direction the tongs are raised again without the electrode participating in this movement since, as described in the foregoing, a force-operated effect cannot occur with this movement between the tongs and the electrode.

The preferably water-cooled holding ring 8 may be either rigidly mounted or in known manner be moved up and down. One conventional method of mounting the holder together with the electrodes involves the use of the eyes 16 and cables 17 which run on pulleys 18 and can be wound up on the drum 19 by a motor.

This design requires but a very slight height. The electrode may be uniformly released by any amount without interrupting the current. But with known types, although they are operating without current interruption but must completely release the jaws, there is danger of an electric arc being formed between the jaws and the electrodes. This disadvantage is avoided by the invention.

In the design according to Figure 2 the electrode 1 is held in rest position by the four jaws 6 of the lower clamp holder. For this purpose there are arranged in cups the springs 2 exerting a compressive effect on the bars 9. The spring pressure is transmitted to the plungers 5 by means of the links 3 and the toggle 4. The arrangement 2 to 1 is accommodated in a cooled ring-shaped casing 1 carrying in its upper part removable and follower-like closed spring heads 30. Tension of spring 2 may be adjusted by adjustment of bolts 25 acting upon spring head 30. At that place are also suspended in hinged arrangement the jaws 6. The upper clamp carries the jaws 14 on bars or holders 11 on which are rotatably fastened the spindle nuts 10. The chain 13 in this mode of construction serves for the common actuation of all the nuts 10.

In order to supply electric current to the electrode 1, a current lead-in 23, water cooled, is connected with the jaw 6. Numeral 24 designates the flexible leads connecting lead-in 23 with a current source not shown. The various jaws 6 are electrically connected to each other, said jaws being flexibly suspended to the holding ring by means of a link 20 and joints 21.

Since the nature of the invention involves transmission of occurring clamping forces and liberating forces in the mechanically simplest form, namely, by pulling forces or compressing forces, and to keep the transmitting components at least theoretically free from bending stresses, importance is attached in all modes of construction to guiding all screw spindle bars 9 perpendicular and exactly parallel to one another. For this reason also the legs of the tongs (holders) which are rotating, though but slightly, around their axis of rotation—due for example to elastic deflection of the holders, unequal thickness of the electrodes, backlash at the axis of rotation et cetera—must be connected to the ball joint comprising the ball members 10' and ball cup 10'' with the screw spindle bars by an intermediate member. The Figures 4, 5 and 6 show the effective and extreme position of the ball joint in exaggerated representation. The spindle system at the spindle heads is stiffened by a ring in consequence of the fact that in practical design

there are transmitted to the spindle also over the ball joint and the bearing surface, respectively, slight frictional forces between the ball cup and the nut, which would exert a bending strain on the spindle.

According to the invention the especially simple design according to Figure 3 embodies a finely-adjustable clamping holder actuated by oil or water pressure. The jaws of the lower clamp 6 are pressed-on in the operating position of the electrodes by the pistons 5. The ring 1 contains the cooled piston space 8 and means for supplying the pressure medium. The screw spindle 9 is also subjected to the action of the pressure means on piston 5a through conduit 5b (shown on the left hand side of the drawing) and a spring 2, described in the foregoing, or an elastic pressure means, such as compressed air over the piston in equilibrium, as described in the foregoing. The upper clamps 14 are arranged in holders 11 (compare Figure 4); 13 is the common actuation for the spindle nut 10. Nut 10 acts upon holder 11 through angle member 29, see Figures 1 and 2 as well as Figure 3.

From a pressure means tank, not shown, is conducted a noncompressible medium (water, oil) through the shut-off valve 31 into the pressure cylinder communicating with the piston which is filled until the pressure piston assumes about the position shown in the drawings. When in this position the shut-off element is closed and used later exclusively for refilling if there has occurred a loss of pressure means, if any. The spring 2 is tensioned to such an extent that the pressure exerted by it over the pressure piston produces a bearing pressure of the piston 5 on the jaw 6 permitting of holding the weight of the electrode. The mode of operation of the upper clamp is again the same. Turning the screw over a common driving means, for example, the chain 13, exerts a pulling force on the spindle 9, owing to the fact that the upper clamp is self-stopping, and relieves the pressure piston whose reduced pressure adapts itself to the piston. The pulling force at the spindle transmits itself as reactive force over the upper clamp to the electrode and increases the weight of the electrode—the electrode slides. The screws having been set at rest, the spring regains its original tension and thereby also the pressing-on force will be regaining its original value which will be able to maintain the electrode in the rest position. Equilibrium is re-established.

The design according to Figure 7 shows an especially completely equipped development.

The circular casing 1 is designed as protective jacket. At its cooled cover in form of the supporting ring 8 are suspended the jaws 6 of the lower clamp for the electrode 1, simultaneously serving for current supply. The protective jacket 1 contains also the lower ends, loaded by the pressure springs 2, of the spindle bars 9, jointly carrying a wedge-shaped ring 32 coaxing with the corresponding counter wedges 22 cast or otherwise attached on the outer surface of the jaws 6. The sleeve 15 serving for permitting the passing of the screw spindle 9 through the carrying ring 8 serves simultaneously for affecting the tension of the pressure spring 2 (pressure readjustment).

In accordance with the other modes of construction the jaws 14 of the upper clamp are arranged in holders permitting free passage of the spindle bars 9. Rigidly connected to the jaw holders, but rotatably arranged opposite them, are the spindle nuts 10, the chain 13 serving for

their common drive. The perpendicular position of the spindle nuts 10 opposite the jaws 14 with the readjusting motion in the sense of the maintenance of pure compression forces and pulling forces, is also secured in this mode of construction by a crowned intermediate bearing similar to that shown in Figure 4. The eyes 16 at the carrying ring 8 are serving for the suspension of the entire arrangement.

The spring 26 of Figure 2 and the spring 26a of Figure 7 serve to increase the clamping effect of the tongs when the electrode is to be moved downward and it is necessary to avoid lifting the tongs too far away from the electrode when nut 10 is traveling upward.

Corresponding to the designs described in the foregoing, in their rest position, namely, in the operating position, the jaws 6 of the lower main clamp are firmly pressed against the electrode 1. For this purpose is serving the keying between the outer surface of the jaws and the wedge-shaped ring, assisted by the springs 2. When rotating the spindle nuts 10 by actuating the chain 13, so that the spindle 9 is lifted against the action of the springs 2, the pressing-on of the wedge-shaped ring and corresponding thereto the clamping effect of the jaws will be decreased. But at the same time the spring load of the spindle 9 and its nuts 10 will be augmented by the tension of the springs 2. The spindle nuts will press to the extent of their rotation over their crowned base on the holders of the auxiliary clamping jaws 14, pressed accordingly against the electrode.

What is claimed is:

1. An electrode holder comprising, a main clamp designed as a current conduit for holding an electrode in operating position, means for supporting said main clamp, a secondary clamp axially spaced from said main clamp and adapted to act on another portion of an electrode, means normally pressing said main clamp into gripping position, and means acting on said last-named means for drawing said two clamps together and simultaneously displacing the pressure thereof from the main clamp to the secondary clamp to permit passage of the electrode through the former.
- 15 2. An electrode holder comprising, a main clamp designed as a current conduit for holding an electrode in operating position, means for supporting said main clamp, a secondary clamp axially spaced from said main clamp and adapted to act on another portion of an electrode, a rod operatively connecting said clamps, a spring 20 acting through said rod to normally bias the main clamp to gripping position and the secondary clamp to release position, and means for simultaneously shortening the effective length of said rod and compressing said spring to relatively move said two clamps toward one another and to displace the thrust of said spring from said main clamp to said secondary clamp to permit passage of the electrode through the former.
- 25 3. An electrode holder comprising, a main clamp designed as a current conduit for holding an electrode in operating position, means for supporting said main clamp, a secondary clamp axially spaced from said main clamp and adapted to act on another portion of an electrode, a rod operatively connecting said clamps, a spring 30 acting through said rod to normally bias the main clamp to gripping position and the secondary clamp to release position, and means for simultaneously shortening the effective length of said rod and compressing said spring to relatively move said two clamps toward one another and to displace the thrust of said spring from said main clamp to said secondary clamp to permit passage of the electrode through the former.
